BRUSH WITH CEMENTED TUFT SOCKET

Lewis W. Simms, Fairville, New Brunswick,
Canada

Application October 28, 1944, Serial No. 560,763

7 Claims. (Cl. 15—192)

1

This invention relates to brushes of the paint brush type.

It is an object of the present invention to provide an improved brush construction employing a combined bristle and handle securing unit of reinforced yet simple character which will not tend to spring or yield and which will secure the bristles and secure the handle without the necessity of employing nails, rivets and the like.

A further object of the invention is to provide a brush of this kind employing a bristle-secur ing and handle-secur ing unit which is made of a plurality of parts readily secured together as a unit in a simple and efficient manner.

A still further object of the invention is to provide a brush of this kind wherein the bristle securing unit may be made of minimum size and into which the butts of the bristles are projected into the ferrule only to a limited extent, making it possible to use a shorter length of bristle than in the case of usual and conventional structures.

A still further object of the invention is to provide a brush structure wherein the handle may be formed of plastic material and moulded and secured to the handle receiving portion of the holding unit in a simple durable and secure manner.

A still further object of the present invention is to provide a brush of this character in which the bristles may be secured in the ferrule and the handle secured to a receiving element in separate operations and the two parts secured together in a simple operation to form the complete brush.

With these and other objects in view the invention generally comprises a bristle holding unit, including a ferrule into which the butts of the bristles may be projected, a bristle securing element slidably fitting within the ferrule and co-operating with plastic material to retain the bristles solidly in position, a handle securing element slidably fitting within the ferrule and engaging the bristle securing element, and means in connection with the ferrule for jointly securing the ferrule, bristle securing member and handle securing element together. The handle securing element is specially formed to receive a handle without the necessity of nails, rivets or the like and is particularly adapted to secure a moulded plastic handle.

The invention will be clearly understood by reference to the following detailed specification taken in conjunction with the accompanying drawings.

In the drawings,

Fig. 1 is a front elevation of a brush of the paint brush type.

Fig. 2 is a side elevation of Fig. 1.

2

Fig. 3 is a longitudinal section taken through the brush shown in Fig. 1.

Fig. 4 is a longitudinal section taken through the said brush at right angles to the section shown in Fig. 3.

Fig. 5 is a bottom plan view of the ferrule incorporating the bristle securing element and illustrating in dotted lines the opening through which the handle is secured.

10 Fig. 6 is a longitudinal section taken through the unit shown in Fig. 5.

Fig. 7 is a transverse section taken through the unit shown in Fig. 5.

15 Fig. 8 is a fragmentary sectional detail of the bristle and handle securing unit prior to fastening the elements thereof together as a unit.

Referring to the drawings, A indicates a brush as a whole formed according to the present invention, which includes the bristles B carried in 20 a bristle and handle securing unit C and a handle D. The bristle and handle securing unit is comprised by a main ferrule 10, a bristle securing element 11, slidably fitting within the ferrule, and a handle securing element 12 likewise slidably fitting within the ferrule.

The bristle securing element 11 may take several forms, a known form of such element being illustrated in the present disclosure. This takes the form of a channel element having the base 13 and continuous peripheral wall 14, the base 13 being died to form the openings 15 and the angular projecting tongues or lugs 16, the terminals of which are bent to lie substantially parallel to the base 13. These latter portions of the tongues 16 form the line of contact of the butt ends of the bristles when they are projected in normal position within the ferrule. The free extremities of the walls 14 of the securing element 13 are bent at right angles to form a peripheral projecting flange 17. The ferrule at its normal upper end is offset outwardly and enlarged as at 18 so that the peripheral flange 17 of the bristle securing element 13 may, when the element is slidably projected into the ferrule 10, be disposed within the confines of the ferrule. The handle securing element 12 is formed at its normally lower end with a peripheral flange 19 which is designed to be slid into the enlarged end of the ferrule and into abutment with the flange of the bristle securing element. Thus, by spinning or rolling the enlarged offset portion of the ferrule into engagement with the abutting flanges of the bristle securing element 13 and the handle securing element 19, these elements and the ferrule are readily locked together as a complete rigid unit.

50 The handle securing element is likewise of

channel formation, being provided with the peripheral side wall 20 from which the flange 19 is bent, and it is also provided with a top plate 21 from which the peripherally extending, inclined wall 22 is struck, forming, in effect, a ferrule-like projection or handle ferrule.

In assembling the brush the butts of the bristles B may be inserted within the ferrule 10 and including a suitable spacer or wedge where desired, and the bristle securing element 11 is then projected into the open end of the ferrule until the faces of the tongues or lugs 16 engage the butts of the bristles B. A suitable cement is then poured into the open end of the ferrule so that it will pass through the openings 15 and into the butts of the bristles, and, as indicated at 25, will partially embed the bristle securing element so that the bristles and said latter element are firmly locked together.

The handle securing element 12 may be placed in correlation to a suitable mould for forming a plastic handle. Thus, by employing a suitable stop plate positioned within the handle receiving element which stops the flow of plastic from the mould at a predetermined point, and preferably coinciding with the base of the converging ferrule 22 of said element, the plastic material may be caused to enter this latter ferrule and when set is locked securely with the handle receiving element. In this connection the handle is so moulded that a peripheral shoulder 22a extends therefrom over the free ends of ferrule 22, thus securing the handle from axial movement in either direction.

It is but a simple operation to project the handle receiving element with its attached handle into the open end of the ferrule 10 until the flanges of the bristle securing element and handle securing element are in abutment with one another, whereupon the enlarged portion of the ferrule 10 is suitably clinched, such as by spinning or rolling it around the dual projecting flanges 17 and 19 formed respectively on these elements. In consequence, therefore, the three elements, namely, the ferrule 10, the bristle securing element 11, and the handle securing element 12, are locked together as an inseparable rigid unit to produce a substantially unitary brush member which incorporates a solidly attached plastic handle. If desired, of course, a handle other than plastic might be employed, but the former is desirable from several points of view.

Alternatively, in securing the bristles within the ferrule 10, the latter may be slipped over the bristles and the flag end of the bristles may be dipped in a suitable adhesive which will temporarily set them. The ferrule may then be slipped down on the stiffened bristles and the then projecting butt ends of the bristles may be dipped in a suitable cement up to a desired level. This method provides for a uniform infiltration of cement since the cement will naturally seek its own level in the dipping operation, and after this operation has been carried out the ferrule is moved back to encase the butt end of the bristles. The bristle securing element 11 may then be inserted and cement poured in the open end of the ferrule to the desired level.

The construction described provides a very strong and durable structure which, due to the combination of elements employed, presents a reinforced ferrule structure which will not tend to bow. Thus, this eliminates the use of nails or rivets often employed to offset bowing tend-

encies in the usual type of ferrule, while also eliminating the necessity of nails, rivets, or the like for securing the handle. The elimination of nails or rivets produces an improvement in appearance which is an advantage. Of perhaps greater importance are two further advantages. On the one hand, nails or rivets, as in the first instance, tend to make splits in the bristles resulting in a brush fingering during use. On the other hand, such nails or rivets are apt, in many cases, to cut the bristles off in the path of the rivets, thus weakening the setting and allowing the bristles to come out at such points. Likewise, the nailed handles sometimes split as the nails are passed through them, and serious disadvantages of this kind are completely eliminated according to the present invention.

Finally, several further advantages are produced. In one instance, the necessity for a relatively deep penetration of the bristle butts into the ferrule is eliminated as the bristles may be set firmly without the necessity of deep penetration, and a suitable overall depth for the bristle setting compound and wooden handle. This permits the use of shorter bristles obtained at a lower cost while maintaining a fine quality of brush, which is of particular importance in the use of nylon bristle. Moreover, the shortening of the depth of the ferrule permits the hand of the operator to be nearer to the bristles, which is an important factor in keeping a balance and in lessening the leverage that an operator has to use in applying paint. It also provides for the use of a plastic handle not possible with the usual type of ferrule construction, and this although more costly than wood offers certain offsetting advantages by the elimination of steps of production. On the one hand the plastic handle comes from the moulds with a very high finish and with the trade names and/or brand names already on it as produced by the mould, and in this manner without additional steps it is possible to produce a hole in the handle for suspension purposes when the brush is not in use, which is particularly necessary in the case of nylon bristles which, if left to rest upon the bottom of a container, under the weight of the brush, will bend and cannot be straightened out again, so that the brush is therefore ruined. The handle can also be produced in various desirable colours through moulding with coloured plastic material. In all, therefore, the separate steps of placing the name on the brush handle, the dipping and drying of the handle and the separate nailing step are completely eliminated.

The sturdy construction of bristle and handle securing unit lends itself to the use of nylon bristle which ordinarily is harder to hold in setting than ordinary bristles. The strong assembly of this securing unit produces a safety margin against dislodgement of these bristles.

What I claim as my invention is:

1. A brush comprising a combined bristle and handle securing unit including a ferrule, a bristle securing element fitting within the ferrule, a cementitious material substantially embedding said element and penetrating said bristles to anchor the latter in the ferrule, and a handle securing element fitted in said ferrule and engaging said bristle securing element, said ferrule being deformed to engage with said bristle securing element and said handle securing element adjacent their points of abutment with each other to retain the latter two aforementioned elements in firm, non-yielding engagement to

form a rigid bristle and handle securing unit, and a handle anchored at one end in said handle securing element.

2. A brush as claimed in claim 1, in which the bristle securing element and the handle securing element are formed with corresponding laterally projecting peripheral flanges designed to abut one another when said parts are in engagement, said ferrule being deformed to envelope said flanges in firm bearing engagement therewith to form said rigid unit.

3. A brush as claimed in claim 1, in which said handle securing element comprises a channeled member having a peripheral wall depending from a top plate, the latter having a central orifice surrounded by an outwardly projecting ferrule extension, the defining wall of the latter being inclined, and a handle having one end shaped to correspond with the ferrule portion of said element, the latter being designed to surround and secure said end of the handle.

4. A brush comprising a combined bristle and handle securing unit including a ferrule, a bristle securing element fitted within the ferrule, a cementitious material partially embedding said element and penetrating said bristles to anchor the latter in the ferrule, and a handle securing element fitted in said ferrule and engaging said bristle-securing element, said ferrule being deformed to engage with said bristle securing element and said handle securing element adjacent their points of abutment with each other to retain the latter two aforementioned elements in firm, non-yielding engagement to form a rigid bristle and handle securing unit, said handle receiving element being formed with a ferrule portion to receive a handle, and a plastic handle connected with said handle receiving element by moulding and secured within the ferrule portion of the handle securing element.

5. A brush comprising a combined bristle and handle securing unit including a ferrule enlarged at one end and forming a shoulder therewithin, a perforated bristle securing element having side walls and a lateral outward projection fitted within the ferrule, said outward projection fitting within the enlarged portion of the ferrule and engaging said shoulder, cementitious material partially embedding said element and penetrating the bristles of the brush to anchor said bristles in the ferrule, a handle securing element having a ferrule portion for receiving a handle and a laterally outward projection fitted within said ferrule, the lateral projection thereof being designed to abut said lateral projection of said bristle securing element, said enlarged portion of the ferrule being deformed to engage said lateral projections of the bristle securing element and handle securing element in firm non-yielding engagement to form a rigid bristle and handle securing unit and a handle anchored in the ferrule-like portion of said handle securing element.

6. A brush comprising a combined bristle and handle securing unit including a ferrule, formed with an enlarged end, a bristle securing element in the form of a channelled member having a perforated base and peripheral side walls fitted within said ferrule, one edge of the peripheral walls of said bristle securing element being laterally projected and fitting within the enlarged portion of the ferrule, cementitious material partially embedding said element and penetrating the bristles of the brush to anchor the latter in the ferrule, a handle securing element of channelled form having peripheral walls and a top, one edge of the peripheral walls being laterally projected, said handle securing element being fitted into the enlarged portion of said ferrule and having its laterally projected edge disposed in abutment with the laterally projected edges of said bristle securing element in the enlarged portion of said ferrule, the enlarged portion of said ferrule being deformed to engage the abutting laterally projected edges of said bristle securing element and said handle securing element in firm yielding engagement to form a rigid bristle and handle securing unit, one end of said handle securing element being formed to receive and secure a handle.

7. A brush comprising a combined bristle and handle securing unit including a ferrule, a bristle securing element fitted within the ferrule, a cementitious material partially embedding said element and penetrating said bristles to anchor the latter in the ferrule, a handle securing element fitted within the ferrule and designed to abut said bristle securing element, said handle securing element having an orificed end, the defining edges of the orifices being projected to form a ferrule member and a moulded plastic handle adapted to fit into the ferrule member of said handle securing element, said ferrule being deformed to engage with said bristle securing element and said handle securing element adjacent the points where said two latter mentioned elements abut each other in firm non-yielding engagement therewith to form a complete brush unit.
